UNITED STATES PATENT OFFICE.

CARL MAIRICH, OF BERLIN, GERMANY.

BAKEHOUSE OVEN.

Application filed December 2, 1925, Serial No. 72,777, and in Germany November 29, 1924.

The invention relates to a drive for bakehouse ovens of the continuous type.

In known ovens of this type the carriers (trucks, swing plates, trays, &c.) conveying the material to be baked are actuated by a chain drive which extends the full length of the oven. Owing to the great length of these ovens, special devices are required for keeping the chains in tension, and these devices load the drive unfavorably. At the same time, means must be provided to counterbalance the expansion of the chains when hot. Moreover, the chains must not be freely exposed, but must slide or be drawn through long guides, which cause wear and losses by friction, more particularly since lubrication is out of the question in the circumstances. In the event of a chain breaking, the entire circulation of the carriers is interrupted and the plant put out of action.

According to the invention, these defects are eliminated by arranging that the carriers for the material to be baked are moved onward in succession by separate, complete sets or units of conveying devices provided in a plurality of positions in the course taken by the carriers through the oven. Hence the conveying units for the carriers of the latch 30 are not led right through the oven, but only through a portion thereof, the carriers being, in each case, delivered by one unit to the next in front and then conveyed onward by the latter. When chain drive is employed, 35 only short lengths are used, which do not require special guiding. The influence of the expansion due to heat is rendered practically negligible. Damaged members of the conveying units can be replaced without stopping the work. The insertion of the batch 40 carriers into the oven and their discharge therefrom can be accelerated without interrupting the circulation of said carriers, inasmuch as the rate of movement of the driving mechanism at the ends of the oven is 45 adjustable. Further, particular advantage arises from the gain in time secured by the accelerated insertion of the batch into the oven, so that the batch can be dealt with, according to the character of the dough, without affecting the regularity of the working 50 process.

An oven embodying one form of the invention is illustrated, by way of example, in the accompanying drawing.

Fig. 1 represents a vertical section through

the oven; Figs. 2^a, 2^b represent a horizontal longitudinal section through the oven; Fig. 3 represents a cross section along the line A—B of Fig. 2^a; Fig. 4 is a longitudinal sectional part elevation showing one part of the arrangement of Fig. 1 in a larger scale, and Fig. 5 is a section along the lines C—D of Fig. 4 and Fig. 2^a.

Fig. 6 is a side view elevation showing the front side of the oven with the means for raising the carriers.

In the embodiment shown, the oven has two baking chambers *a* and *b*, with return passages *c*, *d* underneath, through which the carriers *e* are passed in uninterrupted circulation. The carriers *e*, which take the form of trucks, are inserted into the baking chambers at *f*, *f'*, and are taken out at *g*, *g'*.

Distributed at intervals along the oven are chain drives *h*, *i*, *k*, *l* for the forward movement, and *h'*, *i'*, *k'* and *l'* for the return movement of the trucks *e*. The conveyance of the trucks is effected, for example, by drivers *m* attached to the chains *m* and cooperating with stops *e'* and *e''* fixed at the trucks *e* at different height as may be seen from Fig. 5. The stops *e'* are—as may be seen from Fig. 5—arranged in such a manner that they are acted upon by the drivers *m* of the chains *m* when these are passing the underside of their way in the baking chambers *a* and *b*; whereas the drivers *m'* in the return passages *c* and *d* are cooperating with the stop *e''* when they are at the upper sides of their respective ways. The chain wheels *n* of the chain drives are arranged on the inner side walls of the oven and are mounted thereon. All the chain drives *h*, *i*, *k*, *l*, and *h'*, *i'*, *k'*, and *l'* of the oven are driven from a common main shaft *q* arranged as the main shaft (Figs. 1 and 4). This shaft drives by means of a worm wheel drive *x* a plurality of cross shafts *p*, one for each driving unit and driving by means of cone pinions *y* externally mounted vertical shafts *o*, so that the uniform movement of the chains on both sides is ensured. The speed of the middle driving units *i*, *k*, and *i'*, *k'* is usually uniform and adapted to be regulated in common by changing the rotation velocity of the main shaft *q*. The units *h*, *l* and *h'*, *l'* at the ends of the oven can be run however at different speed. The shafts *q'* arranged at the ends of the oven are for instance driven from the main shaft *q* by means of a gearing *t*, an intermediate

Fig. 1 represents a vertical section through

shaft t' and a variable speed gearing u of any well known form. The shaft q' drives the vertical shafts o' (which are arranged similar to the shafts o) by means of the worm wheel drive x' and the bevel gears y' . The means for driving the units l at the other end of the oven are not shown in the drawing. Between the drives l and the main shaft q intermediate gearings, similar to those between the shaft q and the drives h at the front side of the oven, are interposed.

In particular the drives of the units h , h' and l , l' respectively at both ends of the oven are arranged in such a manner that during the charging or discharging periods the units may be periodically run at a relatively high speed and then stopped or slowed down whilst the middle units i , k , i' , k' are still running at a uniform speed. In the constructional form as shown by Figs. 5 and 6 the running of the drives h , h' is made dependent on the opening and closing of the oven doors f and f' acting by means of a lever train w , w' on clutches r , r' arranged at the shafts o' . As soon as the door f at the entrance side of the chamber a is opened, the lever train w connected with the side of the door acts upon the clutches at both sides of the oven connected with it and brings the drive h into action, so that the carriers e being within the reach of the side unit h are pushed forward whereupon a fresh carrier e may be introduced through the oven door. As soon as the door is closed again the unit h is brought to a standstill so that the carrier e just introduced into the baking room stops as well.

The same applies to the doors at the exit ends of the rooms c and d . As soon as such a door is opened the driving unit comes into action and pushes the carrier out of the oven.

The carrier e leaving the rooms c and d at the front side of the oven may be raised to the height of the rooms a and b by means of automatically acting elevators shown by way of example in Figure 6, which, however, do not form a part of the present invention. The vertical shaft S drives the horizontal shaft H by means of the reversible gearing R in one or the other direction. This reversible gear is automatically controlled by means of a cam C , driven from the shaft S , by means of the worm gearing W .

In the position shown in the drawing the elevator E has just been raised by the threaded shafts L to the height of the door f and loaded with articles to be baked. At this moment the door f has to be opened and the carrier e is then introduced into the oven as described above. The elevator E is lowered into its other position in front of the door of the return part of the oven. This is caused by the cam C as will be easily understood from the drawing. The crank lever R' of the reversible gear is rotated so

that the other half of the clutch of the reversible gear comes into operation, this oscillation being caused by the cam C . This operation of the cam C is repeated, causing the elevator, which has in the meantime received an empty carrier, to be raised again. It is understood that similar means are arranged at the other oven end for automatically lowering the carriers with the baked goods leaving the rooms a and b to the height of the return chambers c and d .

The chain drives may also be replaced by other members, such as pinions which gear with racks on the trucks c .

Having now fully described my invention, what I claim and desire to secure by Letters Patent is:—

1. In a bakehouse oven of the continuous type, an oven chamber, means for conveying the batch carriers through the oven chamber comprising a plurality of spaced conveying units arranged in series along the path of the carriers so as to act in succession thereon, and means for stopping the units at the entrance and exit of the oven and subsequently driving the said units at a higher speed than the speed of the remaining units after each stopping period.

2. In a bakehouse oven of the continuous type, an oven chamber, means for conveying the batch carriers through the oven chamber comprising a plurality of conveying units arranged in series along the path of the carriers so as to act in succession thereon, means for driving the units from outside the oven chamber, means for alternately driving at high speed and stopping units adjacent the entrance and exit of said chamber, and means for opening and closing said chamber, said stopping means being actuated by said closing means.

3. In a bakehouse oven of the continuous type, a plurality of oven chambers, a door for each chamber, a plurality of conveying units for the carriers arranged in series in the oven chambers at each side thereof so as to act in succession on the carriers, a shaft for each of the units projecting through the oven, a vertical shaft for each set of superposed units, gears operatively connecting the vertical shafts and said projecting shafts, cross shafts and gears above the oven operatively connecting the vertical shafts at one side of the oven with those at the other side, longitudinal driving shafts, gears operatively connecting said driving shafts with said cross shafts, a clutch interposed between one of the driving shafts and said projecting shafts, and means connecting said clutch with the oven door whereby the clutch is rendered operative on the door being opened and inoperative on the door being shut.

4. In a bakehouse oven of the continuous type, an oven chamber, a plurality of aligned

conveying units for the batch carriers arranged in series along the path of the carriers through the oven chamber so as to act in succession and in the same direction 5 thereon, each unit comprising a short chain drive, the said units being arranged at spaced intervals in such a manner that the whole length of the said conveying units is only a part of the length of the travel of 10 the said batch carrier.

5. In a bakehouse oven of the continuous type, an oven chamber, the combination of a plurality of spaced conveying units arranged in series at each side of the oven 15 chamber along the path of the batch carriers so as to act in succession thereon, means outside of the oven chamber operatively connecting the said plurality of units at one side of the oven with the opposite 20 units at the other side, and means for connecting said first mentioned means with a driving source.

6. In a bakehouse oven with a baking chamber, a return chamber for the batch 25 carriers below the baking chamber, a plurality of conveying units for the carriers arranged in series in said chambers so as to

act in succession on the carriers, means at both sides of the oven operatively connecting the units in the baking chamber with 30 those below in the return chamber, and means operatively connecting said first mentioned means with a driving source.

7. In a bakehouse oven of the continuous type, a baking chamber, a return chamber 35 below the said baking chamber, a plurality of conveying units for the carriers arranged in series in the oven chambers at each side thereof so as to act in succession on the carriers and superposed for the baking and return chamber respectively, a shaft for each of the units projecting through the oven, a vertical shaft for each set of superposed units, gears operatively connecting the vertical shafts and said projecting shafts, cross 40 45 shafts and gears above the oven operatively connecting the vertical shafts at one side of the oven with those at the other side, a longitudinal driving shaft, and gears operatively connecting said driving shaft with said cross 50 shafts.

In testimony whereof I affix my signature.

CARL MAIRICH.
